UNITED STATES PATENT OFFICE.

WILLIAM HENRY HAWKEN, OF HONESDALE, PENNSYLVANIA, ASSIGNOR TO
T. B. CLARK & CO., OF SAME PLACE.

DESIGN FOR THE ORNAMENTATION OF GLASSWARE.

SPECIFICATION forming part of Design No. 19,780, dated April 29, 1890.

Application filed February 25, 1890. Serial No. 341,758. Term of patent 14 years.

To all whom it may concern:

Be it known that I, WILLIAM HENRY HAWKEN, of Honesdale, in the county of Wayne and State of Pennsylvania, have invented 5 and produced a new and original Design for the Ornamentation of Glassware, of which the following is a specification.

The drawings represent in Figure 1 a bottom view of a glass dish containing the design, and in Fig. 2 a transverse section. This 10 design is intended for the ornamentation of glassware of any form to which it is applicable. It is shown upon a shallow dish, but it may be applied to bowls, stem ware, decanters, jugs, &c.

The main lines or grooves of the design are the grooves a a' and b b' , which form triangles 15 symmetrically arranged in relation to each other to produce the outline of a pointed star. Within the limits of one triangle and parallel 20 with one of its sides are lines a' a' , and within the limits of the other triangle and parallel with one of its sides are lines b' b' . I also 25 form by means of lines or grooves substantially a rectangle, the corners of which are marked d . Parallel with these lines or grooves I have formed interior lines or grooves. One 30 set of these lines or grooves—all parallel with each—I have marked 1 2 3 4. The lines which form the two sides of the rectangle, and with the lines 1 4 bound the same, are marked 5

8, and the interior lines parallel thereto are marked 6 7. It will be observed that the lines a' and b' , together with the boundaries of the triangles above specified, form diamond-shaped figures, while the numbered lines just above mentioned cut these diamond-shaped figures into six-sided figures corresponding to and lying within the hexagon of the star, which is bounded by the lines d and e , all of 35 these above described constituting the main figure of the design. A central subordinate hexagon f lies within the interior lines above described, and the surrounding hexagons 10 11 12 13 14 15 are subdivided centrally into 40 45 sections by the numbered and lettered lines above referred to. The faces of these subdivisions are ornamented by grooves either fan and star shaped, as at 16 and 17, or by grooves crossing each other, as at 18, and the intermediate polygonal figures D.

I claim—

The design for the ornamentation of glassware herein shown and described.

In testimony whereof I have signed my 55 name to this specification in the presence of two subscribing witnesses.

WILLIAM HENRY HAWKEN.
